(57) **CLAIM**

The ornamental design for a high definition multimedia interface connector retention apparatus, as shown and described.

DESCRIPTION

FIG. 1 is a perspective view of the high definition multimedia interface connector retention apparatus showing my new design;

FIG. 2 is a front elevational view thereof;

FIG. 3 is a left side elevational view thereof, the right side elevational view being a mirror image;

FIG. 4 is a top plan view thereof;

FIG. 5 is a bottom plan view thereof; and,

FIG. 6 is a rear elevational view thereof.

Any broken line illustration of environmental structure in the drawings is not part of the design sought to be patented.

Portions of the claimed design are shown separated and bound by a bracket to indicate that no particular length is being claimed.
